UNITED STATES PATENT OFFICE.

JOHN KOVACS, OF HOLLISTER, OHIO.

ELEVATOR SAFETY DEVICE.

1,161,136.

Specification of Letters Patent. Patented Nov. 23, 1915.

Application filed January 26, 1915. Serial No. 4,471.

To all whom it may concern:

Be it known that I, JOHN KOVACS, a citizen of the United States, residing at Hollister, in the county of Athens and State of Ohio, have invented certain new and useful Improvements in Elevator Safety Devices, of which the following is a specification.

This invention relates to certain new and useful improvements in safety devices.

10 The primary object of the invention is the provision of an appliance attached to an elevator and whereby the car is automatically locked at a predetermined position within the elevator shaft in the event of accidental 15 breaking of the car hoisting means.

A further object is to provide similar lock devices assembled upon both the upper and the lower sides of an elevator car bottom, such devices being normally held unlocked 20 by the taut car hoisting cable, but instantly releasable for assuming locking engagement with the elevator shaft members upon a severing of the cable.

A still further object of the invention is 25 to provide normally inoperative locking members upon an elevator car adapted to be automatically released in the event of an accident to the hoisting mechanism and thus preventing the car from dropping and thereby obviating any injury to the car contents, buffeting supporting means being provided at intervals in the elevator shaft for receiving and supporting the car.

With these general objects in view and 30 others that will appear as the nature of the invention is better understood, the same consists in the novel combination and arrangement of parts hereinafter more fully described, illustrated in the accompanying drawings and pointed out in the appended claim.

In the drawings forming a part of this application and in which like-designating characters refer to corresponding parts 45 throughout the several views, Figure 1 is a front elevation of the framework of an elevator shaft having a car vertically movable therein and provided with the present device, the mechanism being shown in its operative car supporting position. Fig. 2 is a horizontal sectional view taken slightly above the floor of the car with the mechanism casing broken away and showing the mechanism as normally in-operatively positioned. Fig. 3 is a horizontal sectional view taken upon a plane slightly beneath the car

and showing the car bottom in bottom plan and with the mechanism casing removed, the mechanism being shown in its operative released locking position. Fig. 4 is a side elevation of the members shown in Fig. 1, the hoisting cable being severed. Fig. 5 is a side elevation of one of the side guide timbers of the elevator shaft at a point adjacent the supporting notches thereof, and 65 partially broken away, and Fig. 6 is a detail vertical sectional view of a portion of the car bottom and looking toward one end of the car.

Referring more in detail to the drawings, 70 it will be noted that the elevator shaft is provided with substantially the usual form of framework which includes opposite guide beams 10 and a top cross beam 11, the latter adapted to support a pulley 12 over which 75 the hoisting cable 13 of the elevator car 14 is adapted to return, the said car being slidably positioned between the beams 10 and having spaced strips or shoes 15 upon its opposite side plates 16 for slidably receiving 80 the guide beams therebetween, and thus directing the vertical movement of the car in the shaft.

The car floor 17 is provided with identical locking means upon both the upper and 85 lower faces thereof, such means being enclosed within casings 18 secured to the opposite faces of the car bottom as best illustrated in Figs. 1 and 4 of the drawings.

The description of one of the locking 90 means will suffice for both, and identical designating characters will be employed for like elements. Projectable bolts 19 are flatly arranged longitudinally of the car bottom at each end thereof and are slidably mounted within perforations 20 of brackets 21, while the inner reduced ends 22 of the said bolts are slidably mounted through perforations in the smaller brackets 23. Expansion 95 springs 24 encircle the reduced portion 22 of the bolts and tend to normally project the bolts, the said springs being tensioned between the brackets 23 and the shoulders 25 of the bolts.

A bolt operating lever 26 is pivoted as at 105 27 to the car bottom and is provided with flexible connections such as cords 28 between the inner ends of the bolts and joints 29 which are spaced at equal distances at opposite sides of the said pivot 27. The operating lever is provided with a projecting handle 30 having an actuating cord 31 se-

cured thereto, which cord is adapted to pass through a perforation 32 of the bracket 21 and thence over a pulley 33 carried by the adjacent side plate of the elevator, the cord 5 then passing upwardly through staples 34 upon the car roof 35 and being secured to the hoisting cable 13 at a time when the lever 26 retains the locking bolts retracted and with the mechanism positioned as best 10 shown in Fig. 2. It will of course be understood that the cable 13 being normally taut, and the cord 31 at such times holding the bolts in their normal retracted inoperative 15 positions, a severing of the hoisting cable causing a relaxing thereof, releases the springs 24 resulting in an outward projecting of the bolts automatically to their locking or engaging positions, as best illustrated in Fig. 3.

20 It will be noted that the upper and lower locking means are identical excepting that the retaining or drop cord 31 passes upwardly at an opposite side of the car, the free upper ends of both of the said cords 25 being secured as at 36 to the hoisting cable as noted and at a point above the car roof 35.

The guide beams 10 are provided with open notches 37 opening inwardly and having recesses 38 for mounting expansion 30 springs 39 therein and upon the bottoms 40 of the said recesses, while a block 41 is mounted upon the top of each of the said springs. The notches and sockets are arranged in pairs as best illustrated in Fig. 35 5 and are adapted to receive the locking ends of the bolts 19 when the same are projected, it being understood that whenever the hoisting cable is severed, the resiliently 40 projecting bolts 19 will bear against the inner faces 42 of the guide beams, and will slide thereon until the descending car brings the bolts in alignment with the notches 37 when the free ends of the bolts will be projected therein and will enter the recesses 45 38 and being received upon the resiliently mounted blocks 41, the drop of the car will be cushioned and the further fall of the car will be prevented. It will be noted that under some circumstances only one set of the

locking bolts will be engaged with the retaining notches, while the two sets of locking means are provided for insuring a complete operation of the device, while under certain conditions, both of said sets of bolts will engage the receiving notches for retaining the car, it being also understood that these notches and recesses may be arranged at regular intervals throughout the entire height of the guide beams. Cover plates 43 are secured to the opposite sides of the guide 60 beams for closing the opposite sides of the said notches and recesses.

The complete operation of the device will be apparent from this detailed description thereof, the entire mechanism being adapted for installation both upon new and old elevators, the same being easily and cheaply manufactured, although possessing great efficiency in the prevention of accidents.

While the form of the invention herein 70 shown and described is what is believed to be the preferred embodiment thereof, it is nevertheless to be understood that minor changes may be made without departing from the spirit and scope of the invention 75 as set forth in the claim.

What is claimed as new is:—

In a device of the kind described, the combination with vertical guide beams having spaced notches formed on their opposed 80 faces, the notches having flat bottoms and inclined upper faces, a pin projecting upward from the bottom of each notch, a spring mounted upon the pin in each notch, a supporting block secured in the upper end 85 of each spring, cover plates carried by said beams to close the opposite sides of the notches whereby to form sockets, an elevator car slidably mounted between the beams and means carried by the elevator car adapted 90 to engage the blocks when released and stop downward movement of the car.

In testimony whereof I affix my signature in presence of two witnesses:

JOHN KOVACS.

Witnesses:

A. J. CRANFORD,
WM. SEILER.
